UNITED STATES PATENT OFFICE.

ADOLPH KEPPELER, OF BUTTE, MONTANA.

DRINK-MIXING DEVICE.

1,119,168.

Specification of Letters Patent. Patented Dec. 1, 1914.

Application filed April 20, 1914. Serial No. 833,161.

To all whom it may concern:

Be it known that I, ADOLPH KEPPELER, a citizen of the United States, residing at Butte, in the county of Silverbow and State of Montana, have invented certain new and useful Improvements in Drink-Mixing Devices, of which the following is a specification.

This invention relates to devices for mixing liquids by agitating the same, and its object is to provide a novel form of rotary dasher which effects a quick and thorough mixture of the liquid and which is constructed to force the liquid toward the bottom of the glass or other receptacle and thus keeps it from overflowing or splashing out.

In order that the invention may be better understood reference is had to the accompanying drawing, in which a perspective view of the dasher is shown.

Referring specifically to the drawing, the dasher comprises a shaft 5 having a spiral rib 6 which may be a piece of wire, the same being wrapped spirally around the shaft and soldered or otherwise secured thereto. The upper end of the shaft has a head 7 provided with a socket 8 to receive the end of the shaft of the drive motor, to which latter shaft the dasher is made fast by set screws 9 passing through the head. Any other suitable means may be provided for coupling the dasher to the motor or drive shaft. The lower end of the shaft has a conical foot piece 10. The spiral rib extends around the shaft from a point a short

distance below the upper end thereof down to the foot piece.

In operation, the glass or other receptacle containing the liquid to be mixed is placed so that the dasher enters the same, with the foot piece seating on the bottom of the glass. The motor is then started to rotate the beater, whereupon the liquid is quickly and thoroughly mixed by being agitated by the spiral rib 6. The dasher is rotated from the right to the left, and the rib runs in such a direction that when the dasher is rotated in the direction stated, the liquid is forced downward toward the bottom of the receptacle. The liquid is therefore prevented from overflowing or splashing out over the top of the receptacle. When the dasher is in operation the rib 6 is entirely below the surface of the liquid which also prevents it from splashing.

I claim:

A liquid mixing dasher comprising a rotary shaft having a conical foot piece at its lower end and means for agitating the liquid, said agitating means comprising a wire wrapped around the shaft spirally and secured thereto, said wire extending from a point adjacent to the upper end of the shaft and terminating at the foot piece.

In testimony whereof I affix my signature in presence of two witnesses.

ADOLPH KEPPELER.
